Inventor:

Joseph Kenneth Johnson

UNITED STATES PATENT OFFICE

107,153

DESIGN FOR AN ENTREE PLATE

Joseph Kenneth Johnson, Jersey City, N. J.

Application July 2, 1937, Serial No. 70,230

Term of patent 14 years

To all whom it may concern:

Be it known that I, Joseph Kenneth Johnson, a citizen of the United States, residing at Jersey City, in the county of Hudson and the State of New Jersey, have invented a new, original, and ornamental Design for an Entree Plate, of which the following is a specification, reference being had to the accompanying drawing, forming part thereof.

I claim:

The ornamental design for an entree plate as shown.
